UNITED STATES PATENT OFFICE

LOUIS D. HOLMES AND JOHN S. TOWNSEND, OF HARVEY, ILLINOIS, ASSIGNEES TO
WHITING CORPORATION, OF HARVEY, ILLINOIS, A CORPORATION OF ILLINOIS

TRANSFER PLATFORM

Application filed January 9, 1929. Serial No. 331,233.

The invention relates to transfer platforms of the type used for transferring freight between station platforms over the tracks.

The objects of the invention are to provide: an improved structure adapted to be placed over railroad tracks to raise and lower a transfer platform above the top of the cars on the tracks; improved power-operated mechanism for raising and lowering the platform; improved means for controlling the power-mechanism for raising and lowering the platform to cause it to automatically stop when the platform reaches predetermined high and low levels; improved signalling means for indicating the positions of the platform; and other objects which will appear from the description.

The invention consists in the several novel features hereinafter set forth and more particularly defined by claims at the conclusion hereof.

In the drawings: Fig. 1 is a side elevation of a structure embodying the invention. Fig. 2 is an end elevation. Fig. 3 is a plan. Fig. 4 is a section on line 4—4 of Fig. 7. Fig. 5 is a section on line 5—5 of Fig. 7. Fig. 6 is a section on line 6—6 of Fig. 3. Fig. 7 is a section on line 7—7 of Fig. 6. Fig. 8 is a perspective of a portion of the table in partially raised position. Fig. 9 is a perspective of one of the guides between the platform and the beam along which it travels. Fig. 10 is a diagram of the electric circuits for controlling the motor which operates the raising and lowering mechanism and the signalling devices. Fig. 11 is a detail of one of the platform operated switches.

The invention is exemplified in connection with a pair of station floors or platforms *a* which extend longitudinally of a pair of railway tracks *b*. These platforms are usually constructed so as to be level with the floors of freight cars, so that freight may be unloaded from the cars, directly onto the adjacent platform. In distributing freight for loading or after having been unloaded, it is necessary to transfer freight from one of the station platforms or floors to another, and for this purpose a platform *c* is provided

which, when lowered, is adapted to form a bridge between the station platforms or floors, so that freight may be transported from one to the other, and which can be raised a sufficient distance to permit railway cars to pass under it when cars are to be moved on the tracks between the station platforms or floors. This platform is composed of a pair of channel beams 12 and 13 at each end thereof, an I-beam 14 at each side thereof, a central cross-girder 15 formed of an I-beam, and joists or girders 16 formed of channel beams, all rigidly secured together by brackets 17 to form a rigid structure which is adapted to support the required load which it may be desired to transfer from one platform or floor *a* to the other. A floor of boards 18 is laid on top of the beams and girders of the platform *c*. Each platform or floor *a* is formed with a recess *a'* along its edge, to receive the sides of the platform and to form abutments upon which the I-beams 14 of the platform *c* will rest when the latter is in its operative position, and so that the weight of platform *c* and the load thereon will not be imposed on the lifting mechanism while said platform is in its operative position. The supporting structure for the platform *c*, when it is raised, comprises I-beam columns 20 at the corners of said platform respectively. These columns have their lower ends secured by angle plates 21 to plates 22 which usually set in the concrete forming the station platforms. The latter are recessed, as at 23, to receive the lower portions of columns 20, and to secure them laterally. The upper ends of columns 20 are secured together by a rectangular structure comprising side beams 24 and a pair of beams 25 at each end, and corner plates 26, all secured together to said columns to form a rigid rectangular structure. The columns 20 are also secured to the beams 25 by brackets 26^a, and to the beams 24 by brace-bars 26^b. The inner faces of the inwardly extending flanges of each column 20 have welded thereon guide strips 27. A bracket 28 is provided at each corner of the platform *c*, and extends under a pair of end beams 12, 13, and is provided with vertical grooves or ways 109

29 to fit around the guide strips 27 of the adjacent column to vertically guide the platform *c*. The lower flanges of beams and 13 are cut away, as at 30, to receive the upwardly extending portions of bracket 28. 5 These brackets extend under the beams 12, 13, and are operated vertically by the rotation of screws 31, to raise the platform *c* from, and lower it to, its operative position. 10 Each screw 31 is threaded to a nut 32 which is non-rotatably held in a bracket 28, so that, by rotation of the screws, the brackets will be raised and lowered to correspondingly raise or lower the platform *c*. Each screw 31 extends 15 between a pair of beams 12, 13, and its lower end is journalled in a bracket 34 which is rigidly secured in the outwardly facing channel of one of the columns 20. The upper end of each screw 31 is journalled in a 20 sectional gear-case 35 which is mounted on one of the plates 26 of the overhead structure. These cases are adapted to contain lubricant. Mechanism is provided to simultaneously rotate the screws 31 to simultaneously 25 lift the four corners of the platform *c*, and to shift it in a vertical rectilinear path. This mechanism comprises an electric motor 37 which is mounted on a plate 38 on top of the overhead supporting structure; a pinion 30 39 on the shaft of said motor; a gear 40 driven by said pinion; a shaft 41 journalled in bearings 42 fixed to the overhead structure; bevelled gears 43 and 44 on the ends of said shaft 41 respectively; longitudinal shafts 45 35 and 46; bevelled gears 47 and 48 meshing with gears 43, 44 respectively, worms 49, one at each end of shafts 45 and 46, and disposed in the gear-cases 35 respectively, and worm wheels 50 each fixed to the upper end of one 40 of the screws 31 and meshing with one of the worms 49. Motor 37 is of the reversible type, so that when it is driven in one direction it will simultaneously operate through the gearing last described, the four screws 31 45 to raise the platform *c*, and when it is driven in reverse direction, to rotate the screws to lower said platform. Guards or deflectors 51, usually of cast steel, are fixed to the columns 20, to prevent them from being deformed by impact of the trucks used in transferring freight. A vertical series of rods 52 is secured to one of the columns 20 to form a ladder to the overhead structure. 50

55 In practice, it is important to automatically stop the motor and gearing driven thereby when the platform *c* reaches its predetermined high and low limits, and for this purpose a normally and spring-closed switch 56 is secured to one of the columns 20, and is adapted to be shifted by an angle iron lug 55, when the platform reaches its low limit to open the controlling circuit for lowering the platform *c*. A similar switch 56 is mounted adjacent the upper end of said

column, so as to be shifted by said lug to open the circuit for controlling the operation of the motor in lifting the platform *c*. Suitable switch mechanism for controlling the operation and direction of the motor 37 is contained in a box 57 which is secured to one of the columns 20. A manually operable switch 58 controls said switch mechanism, to cause the motor to operate to lift the platform *c*, and a similar switch 59 is connected to control said mechanism to control the reverse operation of motor 37 to lower the platform *c*. These switches 58 and 59 are connected to the mechanism in the box 57 and to the switches 54 and 56, as indicated in Fig. 10. A stop switch 60 is also connected to said switch mechanism, as well understood in the art. 70 75 80

In practice, it is desirable to indicate whether the platform *c* is in its raised position so the tracks will be clear to permit traffic to pass thereover and under the platform. The invention provides distinctive signals, such as red lamps 61, one above each of the station platforms to indicate that the table is not in its raised position to permit traffic over the tracks, and green lamps 62, one above each station platform to indicate that platform *c* is in its fully raised position, so that the tracks are free to permit traffic over them, and means for automatically controlling the lamps. 85 This automatic means comprises a switch 63 adapted to be operated by a lug 55^a on one of the corners of the platform *c* for controlling the signal lamps. This switch is normally spring-pressed against a contact 63^a, so that the red lamps will be actuated at all times, except when the platform *c* is in its fully raised position. Said switch is also adapted to engage a contact 62^b, when shifted by the lug 55^a on the platform *c* when the latter reaches its fully raised position, to close a circuit through green lamps 62. As a result, the red lamps will be actuated at all times to indicate that the traffic over the tracks is blocked, except when the platform *c* is in its fully raised position, at which time the switch 63 will close a circuit to actuate the green lamp 62 to indicate that the tracks are clear. These lamps and switches are electrically connected, as in Fig. 10. Switches 54, 56 and 63 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840

In operation the bridge-platform *c* will be normally in its fully raised position, indicated by dotted lines in Figs. 1 and 2, so the tracks will be clear for traffic. When this platform is in this position, the green lamps 62 will be actuated as the result of the shifting of switch 63 into engagement with contact 62^b, to indicate that the tracks are clear, 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840

said circuit being as follows: conductor 70, switch 63, contact 62^b, conductor 71, in which the lamps 62 are included, and conductor 73. Switch 60 controls the flow of current to the motor and signalling devices. While the platform is in its completely lifted position, lug 55^a will hold the switch 63 open to interrupt the circuit through red lamps 61. To lower the bridge-platform *c* into its operative position to permit freight to be transferred directly between the station platform *a*, the operator will close switch 59 to control the mechanism in box 57 which will cause the motor 37 to be driven in the right direction to rotate the screws 31, to lower the brackets 28 on which the beams 12 and 13 of the platform *c* rest. The motor will continue in its operation until the lug 55 engages the low limit switch 54 as the platform reaches its operative level. The opening of switch 54 will interrupt the motor control circuit through switch 59 and stop the motor. As soon as the platform leaves its completely elevated position lug 55^a will release switch 63 to open the circuit through green lamps 62, and to release said switch, so that it will close a circuit through the red lamps to indicate that the tracks are not clear. The circuit of the red lamps will be through conductor 70, switch 63, contact 63^a, conductor 75, in which the red lamps are included, and conductor 73. This circuit will remain closed until the platform *c* is returned to its completely lifted position. To lift the bridge-platform *c*, to permit traffic over the tracks, the operator will close switch 58 which will control the mechanism in the box 57 to cause the motor 37 to operate in the right direction to rotate screws 31 to lift brackets 28. The motor will continue to operate until the platform reaches its completely lifted position, at which time lug 55 will open switch 56 to interrupt the circuit through switch 58 and cause the motor to stop. Simultaneously, lug 55^a will shift switch 63 to discontinue the red lamps and close the circuit for the actuation of green lamps 62.

The invention exemplifies a rectangular transfer platform which is guided at each of its four corners in or by a column, so that it will be securely confined against lateral displacement. It also exemplifies a device of this character in which the motor and gearing are mounted on an overhead structure supported by the columns to operate rotatable screws for raising and lowering the platform; also a structure of this character which is adapted for heavy loads; also a structure provided with means for automatically stopping the operation of the electric motor when the platform reaches its raised and lowered position, and in which the signalling mechanism, to indicate whether or not the tracks are clear, is automatically controlled by the bridge platform.

63 The invention is not to be understood as re-

stricted to the details set forth, since these may be modified within the scope of the appended claims, without departing from the spirit and scope of the invention.

Having thus described the invention, what we claim as new and desire to secure by Letters Patent, is:

1. In mechanism of the class described, the combination of a set of columns, a structure rigidly connecting the tops of the columns, a vertically movable transfer platform between the columns, and raising and lowering mechanism comprising vertical screw shafts associated with the columns respectively, gearing coacting with the screws and an electric motor, said gearing and motor being mounted above the platform.

2. In mechanism of the class described, the combination of a set of columns, a structure rigidly connecting the tops of the columns, a vertically movable transfer platform between the columns, vertical screw shafts associated with the columns respectively, and held against longitudinal movement, platform-carrying brackets on and operable by the screws, to raise and lower the platform, and mechanism for rotating the screws comprising an electric motor mounted on said structure, and above the platform, and motor-driven gearing for rotating said screws.

3. In mechanism of the class described, the combination of a supporting structure comprising a set of columns, a vertically movable transfer-platform between the columns, vertical screw shafts associated with and supported on the columns respectively, and held against longitudinal movement, platform carrying brackets on and operable by the screws, to raise and lower the platform, and mechanism for rotating the screws comprising an electric motor, and gearing between the motor and said screws.

4. In mechanism of the class described, the combination of a supporting structure comprising a set of columns, a structure rigidly connecting the tops of the columns, a vertically movable transfer-platform between the columns, vertical screw shafts associated with and supported on the columns respectively, and held against longitudinal movement, platform carrying brackets on and operable by the screws, to raise and lower the platform, and mechanism for rotating the screws comprising an electric motor and gearing between the motor and said screws.

5. In mechanism of the class described, the combination of a set of columns, a vertically movable transfer-platform between the columns, vertical screw-shafts associated with and supported on the columns respectively and held against longitudinal movement, platform carrying brackets on and operable by the screws, to raise and lower the platform, vertical guides between the brackets and the columns, and mechanism for rotating the

screws comprising an electric motor and gearing between the motor and said screws.

6. In mechanism of the character described, the combination with a railroad track and station-platforms at the sides thereof provided with abutments, a set of four columns, vertical screws associated with the columns, and held against vertical movement, a transfer platform between the columns and movable to a position above cars on the track, brackets on and operable by the screws, and on which the corners of the platform are supported, the transfer-platform being adapted to rest on said abutments, the brackets being free to be lowered away from the platform when the platform is supported by said abutments, and mechanism for rotating the screws comprising an electric motor, and gearing between the motor and said screws.
- 10 7. In mechanism of the character described, the combination with a railroad track and station-platforms at the sides thereof provided with abutments, a set of four columns, vertical screws associated with the columns, and held against vertical movement, a transfer platform between the columns and movable to a position above cars on the track, brackets on and operable by the screws, and on which the corners of the platform are supported, the transfer - platform being adapted to rest on said abutments, the brackets being free to be lowered away from the platform when the platform is supported by said abutments, guides between the brackets and the columns, and mechanism for rotating the screws comprising an electric motor, and gearing between the motor and said screws.
- 15 8. In mechanism of the character described, the combination with a railroad track and stationary platforms at the sides thereof provided with abutments, a set of four columns, a structure rigidly connecting the tops of the columns, vertical screws associated with the columns and held against vertical movement, a transfer platform between the columns and movable to a position above cars on the track, brackets on and operable by the screws, and on which the corners of the platform are supported, the transfer-platform being adapted to rest on said abutments, the brackets being free to be lowered away from the platform when the platform is supported by said abutments, and mechanism for rotating the screws comprising an electric motor, and gearing between the motor and said screws.
- 20 9. In mechanism of the character described, the combination with a railroad track and station-platforms at the sides thereof, provided with abutments, a series of four columns, a structure rigidly connecting the tops of the columns, a vertically movable transfer platform between the columns, vertical screws associated with the columns, and held against vertical movement, brackets on and

operable by the screws, and on which the corners of the platform are supported, said platform being adapted to rest on said abutments, the brackets being free to be lowered away from the platform when the platform is supported by said abutments, and mechanism for rotating the screws comprising an electric motor mounted on the top of said structure, and gearing between the motor and said screws.

10 10. In mechanism of the character described, the combination with a railroad track and station-platforms, a set of four columns, a vertically movable transfer platform between the columns, comprising pairs of girders at opposite margins, vertical screws associated with, and supported on, the columns, and extending between the girders of said pairs, platform-carrying brackets on and operable by the screws and on which the pairs of girders are supported, and mechanism for rotating the screws comprising an electric motor, and gearing between the motor and said screws.

15 11. In mechanism of the character described, the combination with a railroad track and station-platforms, a set of four columns, a structure rigidly connecting the tops of the columns, a vertically movable transfer platform between the columns, comprising pairs of girders at opposite margins, vertical screws associated with and supported on the columns and extending between the girders of said pairs, platform carrying brackets on and operable by the screws and on which the pairs of girders are supported, and mechanism for rotating the screws comprising an electric motor carried by said structure, and gearing between the motor and said screws.

20 12. In mechanism of the character described, the combination with a railroad track and station platforms, a set of four columns, a vertically movable transfer platform between the columns, comprising pairs of girders at opposite margins, vertical screws associated with and supported on the columns, and extending between the girders of said pairs, platform-carrying brackets on and operable by the screws and on which the pairs of girders are supported, girders between the brackets and the columns, and mechanism for rotating the screws comprising an electric motor, and gearing between the motor and said screws.

25 13. In a transfer platform of the character described, the combination with a railroad track and station-platforms at the sides thereof, of a transfer platform to bridge the stationary platforms, movable to a position above the cars on the track, a series of supporting columns, mechanism for raising and lowering the transfer platform, comprising an electric motor, and signalling means for indicating that the transfer platform is in

or out of its position to clear the cars on the track, controlled by the movement of the platform.

14. In a transfer platform of the character described, the combination with a railroad track and station-platforms at the sides thereof, of a transfer platform to bridge the stationary platforms, movable to a position above the cars on the track, a series of supporting columns, mechanism for raising and lowering the transfer platform, comprising an electric motor, signal lamps mounted on the columns, for indicating that the transfer platform is in or out of its car-clearing positions, and switch-means, controlled by the movements of the transfer platform, for controlling the lamps.

15. In mechanism of the class described, the combination of a set of columns, a structure rigidly connecting the tops of the columns, a vertically movable transfer platform between the columns, vertical screw shafts associated with the columns respectively, and held against longitudinal movement, platform-carrying brackets on and operable by the screws, to raise and lower the platform, mechanism for rotating the screws comprising an electric motor mounted on said structure and above the platform, and motor-driven gearing for rotating said screws, a stop-switch for the motor, and means controlled by the movements of the platform for operating the switch.

16. In mechanism of the class described, the combination of a set of columns, a structure rigidly connecting the tops of the columns, a vertically movable transfer platform between the columns, vertical screw shafts associated with the columns respectively, and held against longitudinal movement, platform-carrying brackets on and operable by the screws, to raise and lower the platform, mechanism for rotating the screws comprising an electric motor mounted on said structure and above the platform, and motor-driven gearing for rotating said screws, a stop-switch for the motor, mounted on one of the columns, and means controlled by the movements of the platform for operating the switch.

17. In mechanism of the class described, the combination of a set of columns, a structure rigidly connecting the tops of the columns, a vertically movable transfer platform between the columns, vertical screw shafts associated with the columns respectively, and held against longitudinal movement, platform-carrying brackets on and operable by the screws, to raise and lower the platform, mechanism for rotating the screws comprising an electric motor mounted on said structure, and above the platform, and motor-driven gearing for rotating said screws, switches for the motor to stop it when it reaches its high and low limits, and means on the platform for operating said switches.

18. In mechanism of the class described, the combination of a set of columns, a structure rigidly connecting the tops of the columns, a vertically movable transfer platform between the columns, vertical screw shafts associated with the columns respectively, and held against longitudinal movement, platform-carrying brackets on and operable by the screws, to raise and lower the platform, mechanism for rotating the screws comprising an electric motor mounted on said structure, and above the platform, and motor-driven gearing for rotating said screws, switches for the motor to stop it when it reaches its high and low limits, mounted on the columns, and means on the platform for operating said switches.

Signed at Harvey, Illinois, this 26th day of December, 1928.

LOUIS D. HOLMES.
